UNITED STATES PATENT OFFICE

RICHARD T. HOSKING, OF WILMETTE, ILLINOIS, ASSIGNOR, BY MESNE ASSIGNMENTS, TO
SHAKEPROOF LOCK WASHER COMPANY, INCORPORATED, OF CHICAGO, ILLINOIS, A
CORPORATION OF DELAWARE

ELECTRICAL CONNECTER

Application filed November 22, 1929. Serial No. 409,148.

This invention relates to clips such as are used to connect electric wires to binding posts, spark plugs, bolts and the like and pertains more particularly to connectors of 5 the general class described in patent to Gribbie, No. 1,697,954, issued January 8, 1929.

A connector of that class is characterized by being capable of locking itself between the nut and the work in such a way that any 10 tendency to wiggle the stem of the connector from side to side, caused by handling the connector wires in the ordinary use of electrical apparatus, will not tend to loosen the nut or impair the conductivity of the assembled 15 connection.

The object of my invention is to improve and simplify the construction of prior clips of the kind adverted to and to perform the above-mentioned anti-wiggling, electric 20 contact, and nut-locking functions, plus certain novel structural features and an improved mode of operation.

The bolt-receiving end of the connector is arranged so that the assembler can push the 25 connector directly upon that part of the bolt which is exposed between the work and the nut when the nut is unscrewed. Furthermore, the bolt-embracing end of the connector is so arranged that after it has been slipped 30 on the bolt in the manner described its arms are made to surround the bolt merely by turning it about its longitudinal axis. Thereafter the connector is prevented from dropping out whenever the nut is partly loosened.

The arrangement prevents the assembler 35 from putting the connector only part way unto the bolt, thereby making a defective connection. It compels the assembler to either leave the connector off the bolt altogether, or else to engage it with the bolt completely.

The locking teeth of the connector are so 40 arranged that they can not catch on the sides of the bolt when the connector is being slipped on or off, thus materially shortening

the time required for assembling, especially in radio and similar work where speed is essential for mass production.

With the foregoing and certain other objects in view, which will appear later in the 50 specification, the invention comprises the devices described and claimed and the equivalents thereof.

In the drawings Fig. 1 is a plan view of a connector embodying my invention, showing two kinds of locking teeth.

Fig. 2 is an end view.

Fig. 3 is a longitudinal edge view.

Fig. 4 is an end view showing the manner of applying the connector to a bolt.

Fig. 5 is an end view showing the connector after it has been turned about its longitudinal axis to completely surround the bolt.

Fig. 6 is a top perspective view of the connector and the bolt.

Fig. 7 is an edge view of the connector applied to a piece of work, the nut positioned for tightening.

Fig. 8 is an end view showing a mode of 70 removing the connector from a bolt without removing the nut.

As shown in the drawings, the general shape and size and configuration of the connector may be that of any of the conventional or convenient forms consisting of a piece 1 of sheet metal or other suitable spring material formed with a bolt-receiving aperture 2 and having a shank 3 to which an electric conduit, not shown, can be conveniently attached in known manner.

Around the bolt-receiving aperture the piece is shaped to present the general form of an annular ring which has a radial slit 4, or is otherwise severed, at a place on its periphery opposite the shank 3, thereby presenting two annular arms 5 and 6 whose extremities are bent respectively upward and downward out of the plane of the connector body to constitute oppositely projecting 90

spring biting teeth or prongs 7, 8. These prongs are then spread apart on opposite sides of the plane of the connector by bending arms 5 and 6 far enough apart to leave a space $4a$ between them of sufficient width to receive the bolt; that is, the space $4a$ between the prongs is approximately the diameter of the bolt.

When the connector is presented to the bolt, the plane of the connector body being held approximately parallel with the axis of the bolt, it can be slipped on the bolt by merely pushing it forward until the spring arms 5 and 6 have straddled and slid past

the bolt on opposite sides thereof. The bolt is thus received in the aperture 2 of the connector. The connector is then turned so its plane is perpendicular to the axis of the bolt, and the nut is screwed down to clamp the spring prongs 7 and 8 between the work and the nut. The prongs act as a lock washer, preventing the nut from unscrewing, and serving to prevent any sidewise wiggling movement of the connector.

The inner edges of the upwardly bent prongs 7 and downwardly bent prongs 8 are kept from catching on the bolt while the connector is being slipped thereon by bending the prongs so their inner faces are parallel with the sides of the bolt, as shown in Fig. 4. The prongs may be formed as shown in Fig. 1 at 9 and 10, that is, bent cornerwise, or they may be bent straight across, as at $9a$ and $10a$.

This device makes it almost impossible for a fast working assembler to produce a defective joint, because the curved arms 5, 6 must be pushed completely past the bolt or else the connector will not remain in place. Proper positioning of the connector on the bolt is thereby assured. The nut can be then rapidly run into place with a quick running nut-tightening tool in the usual way, producing a mechanically strong and electrically efficient joint.

In the foregoing disclosure the connector has been shown and described in its preferred application. It may also be used in a somewhat modified manner, as follows:

It may be assembled on the bolt in the manner of the ordinary closed connector, by removing the nut and sliding the connector down over the end of the bolt. In this case the connector is made normally flat, that is to say, the bends by which arms 5 and 6 are offset from each other, as in Figs. 2 and 3, are omitted. The terminal may be removed from the bolt without removing the nut, by simply giving the connector a twisting movement about its longitudinal axis. The ends of arms 5 and 6 are thus sprung apart sufficiently to slip past the sides of the bolt when the connector is pulled away, as indicated in Fig. 8.

Having thus described my invention, what

I claim and desire to secure by Letters Patent is:

A connector comprising in one piece a shank and two annular spring arms whose inner ends are in one plane, their outer ends being normally bent with their planes spaced apart a distance substantially equal to the diameter of the bolt opening defined by said arms, the ends of the arms being positioned to substantially abut when the arms are sprung into the same plane, said arms having biting prongs formed at their ends.

In testimony whereof, I affix my signature.

RICHARD T. HOSKING.
